(57) **CLAIM**

The ornamental design for an electric connector with a cable, as shown and described.

DESCRIPTION

FIG. 1 is a top plan view;

FIG. 2 is a front elevation;

FIG. 3 is a bottom plan view;

FIG. 4 is a rear elevation;

FIG. 5 is a left side elevation;

FIG. 6 is a right side elevation; and,

FIG. 7 is a scheme of the connector in use with audio-and-video apparatuses.

In the drawings, each figure thereof being of the connector in which the cable is shown broken away to indicate indeterminate length.

The broken lines showing an additional connector with a cable and other stationary connectors are included for the purpose of illustrating environmental structure only and form no part of the claimed design.

1 Claim, 2 Drawing Sheets
